(57) **CLAIM**

The ornamental design for a volatile emitting lantern, as shown and described.

DESCRIPTION

In a preferred embodiment, the nature of this product is a volatile emitting insect control lantern.

FIG. 1 is a top, left, front perspective view of a volatile emitting lantern embodying our new design;

FIG. 2 is a left side elevational view thereof, the right side elevational view being identical to the left side elevational view shown;

FIG. 3 is a front elevational view thereof, the rear elevational view being identical to the front elevational view shown;

FIG. 4 is a top plan view thereof;

FIG. 5 is a bottom plan view thereof;

FIG. 6 is a front elevational view thereof, but with the additional showing of a hanger environment;

FIG. 7 is a top, left, front perspective view of a second embodiment of a volatile emitting lantern embodying our new design;

FIG. 8 is a left side elevational view thereof, the right side elevational view being identical to the left side elevational view shown;

FIG. 9 is a front elevational view thereof, the rear elevational view being identical to the front elevational view shown;

FIG. 10 is a bottom plan view thereof, the top plan view being identical to the view shown in FIG. 4; and,

FIG. 11 is a front elevational view of the second embodiment, but with the additional showing of a hanger environment.

The broken line representations of holes in FIGS. 1-4, 6-9 and 11, and of hangers in FIGS. 6 and 11, are for the purpose of illustration only, and form no part of the claimed design.
